UNITED STATES PATENT OFFICE

RALPH E. OGDEN, OF MOUNTAINVILLE, NEW YORK, ASSIGNOR, BY MESNE ASSIGNMENTS, TO J. EDWARD OGDEN COMPANY, OF NEW YORK, N. Y., A CORPORATION OF NEW JERSEY

EXPANSION SHIELD

Application filed May 3, 1923. Serial No. 636,390.

This invention relates to improvements in bolt anchors of the character employed for obtaining anchorage in walls of brick, stone and cementitious material not adapted to directly receive a threaded member.

One of the objects of the invention is to provide an expansion shield so constructed and arranged as to possess superior gripping qualities.

10 Another object of the invention is to provide a shield and an expanding member for the shield so relatively constructed and arranged as to obtain gripping actions at a plurality of different points or areas 15 throughout the length of the shield.

Another object of the invention is to provide an expansion shield adapted to be used with and expanded by a driven expanding member.

20 Another object of the invention is to provide an expansion shield comprising two exactly similar sections thereby rendering the sections interchangeable and reducing to a minimum the cost of manufacturing.

25 Another object of the invention is to provide an expansion shield particularly adapted for use with a cable clamp.

Another object of the invention is to provide an expansion shield, a cable clamp and a 30 bridle ring so relatively constructed and arranged that the ring has a shank for expanding the shield and also has means for retaining the cable in position.

35 Further objects of the invention will appear from the following specification taken in connection with the drawings, which form a part of this application, and in which

Fig. 1 is an elevational view of one form 40 of expansion shield constructed in accordance with the invention.

Fig. 2 is an elevational view taken at right angles to Fig. 1.

Fig. 3 is an end elevation of the inner end of the shield illustrated in Fig. 1.

45 Fig. 4 is an end elevation of the opposite or outer end of the shield shown in Fig. 1.

Figs. 5 and 6 are transverse sectional elevations taken substantially on line 5-5 and 6-6 of Fig. 1.

50 Fig. 7 is a sectional elevation similar to

Fig. 6, but showing longer tabs than those shown in Figs. 1 to 6.

Fig. 8 is a sectional elevation of the construction shown in Figs. 1 and 2, but illustrating the shield in position in a wall opening and securing an object to the wall and showing one form of expanding element adapted for use in connection therewith. 55

Fig. 9 is a sectional elevation similar to Fig. 8, but showing a screw as the expanding element. 60

Fig. 10 is an elevational view similar to Fig. 1, but showing wider tabs than those shown in Figs. 1 and 2.

Figs. 11 and 12 are sectional elevations 65 taken respectively on lines 11-11 and 12-12 of Fig. 10.

Fig. 13 is a sectional elevation of another form of shield constructed in accordance with the invention in which an encircling 70 band is used in the place of the tabs shown in the preceding figures.

Fig. 14 is a transverse sectional elevation taken substantially on line 14-14 of Fig. 13.

Fig. 15 is an elevational view illustrating 75 another form of shield constructed in accordance with the invention in which the metal at the edges of the shield sections is folded back to provide excess metal.

Fig. 16 is a transverse sectional elevation 80 taken substantially on line 16-16 of Fig. 15.

Fig. 17 illustrates still another form of shield constructed in accordance with the invention, illustrating the shield as corrugated. 85

Fig. 18 is a transverse sectional elevation taken substantially on line 18-18 of Fig. 17.

Fig. 19 is an elevational view showing the shield mounted in a wall opening and securing thereto a cable clamp and bridle ring. 90

Fig. 20 is an elevational view showing another form of bridle ring having the expanding element formed integral therewith, and

Fig. 21 illustrates still another form of bridle ring adapted for use in connection 95 with the shield.

The invention briefly described consists in an expansion shield particularly adapted for use with a driven expanding element. The shield is substantially cylindrical in shape 100

and comprises a pair of exactly similar sections, each section having formed therein depressed portions adapted to receive means for securing the sections together. In certain 5 embodiments of the invention, each section is provided with tabs adapted to engage the other section and in other embodiments of the invention, the sections are secured together by a band engaging both sections. The band and 10 tabs form excess metal and the depressions form internal projections or embossments adapted to be engaged by the expanding element.

The shield also has formed on its outer end 15 a laterally extending flange and in use the shield is adapted to pass through the opening in an object to be secured and the flange is adapted to seat against the object. The shield is particularly adapted for use with a 20 headed expanding element, such as a nail or screw and these elements may be driven into the shield. The head of the expanding element serves to reinforce the flange on the shield. One use of the invention is shown in 25 Fig. 19, wherein a bridle ring and cable clamp are secured to a wall, but other applications or uses of the invention will be obvious to those skilled in the art. When used with a bridle ring or cable clamp, these elements may 30 be secured by any desired form of expanding element, or, as shown in Figs. 20 and 21, the bridle ring may be formed with a shank adapted to enter and expand the shield. Further details of the invention will appear 35 from the following description.

In the particular embodiment of the invention illustrated in Figs. 1 to 7 inclusive, the shield comprises a pair of sections 20 and 21, each section having a flange 22 at its outer 40 end, these flanges forming a single flanged end for the shield when the sections are secured together.

The two sections of the shield are exactly alike and each section has a pair of longitudinally spaced tabs 23 formed at one of its edges and a single tab 24 formed at the opposite edge and disposed intermediate the pair of tabs. The edge of the section having the single tab has formed at each side of said tab 50 a depression 25 disposed in alignment with the tabs of the pair at the opposite edges. The edge of the section having the pair of tabs has formed therein intermediate this pair and in alignment with the single tab on the 55 opposite edge a depression 26. These depressions form inwardly extending protuberances or embossments and are engaged by the expanding element when this element is forced into the shield.

60 When the sections are secured together as illustrated in the drawings, the tabs of each section overlap the other section and seat in the depressions formed therein. These depressions in conjunction with the tabs form 65 an excess of metal which is expanded into

firm, gripping engagement with the inner surface of the wall opening.

The depressions 25 and 26 form shoulders at the ends thereof for confining the excess metal of the tabs and insure the radial expansion of the tabs by the expanding element. 70

Furthermore, the tabs are retained against possible shearing or relative longitudinal movement with reference to the shield. When the shield is expanded the interlocking of 75 the tabs or excess metal in the depressions and engagement of the tabs in the wall opening securely retains the shield against withdrawal.

In the embodiment of the invention shown in Fig. 8, an object 30 has an opening 31 therein of substantially the same diameter as the outer diameter of the shield. The shield is, therefore, passed through this opening and positioned in the wall opening and thereafter an expanding element such as a nail 32 is driven into the shield expanding it into firm, gripping engagement with the wall opening. The nail preferably has a tapered end 33 and a head 34. The head 34 serves to reinforce the flange 22 of the shield thereby aiding and retaining the object 30 in position. 80

The shield may, however, be used in conjunction with a screw 36 such as illustrated 95 in Fig. 9 and this screw may be driven in or screwed into the shield.

The sectional view in Fig. 7 differs from the showings in the preceding figures in that the tabs 37 are longer than the tabs 23 and 24 and it should be understood that these tabs may be made in any desired form or shape. 100

In Figs. 10, 11 and 12, the tabs 39 and 40 are formed wider than those shown in the preceding figures. 105

In the embodiment of the invention illustrated in Figs. 13 and 14, the shield sections 20 and 21 are formed with longitudinal depressions 41 and the sections are secured together by means of an elongated split band 42. The depressions 41 form shoulders in the shield at the ends thereof. These shoulders serve to confine the sleeve or split band 42 and to prevent relative longitudinal movement between the band and shield when the sleeve is inserted or driven into the opening and to prevent withdrawal of the shield after expansion thereof. This band forms excess metal which is forced outwardly when the expanding element is driven into the shield and engages the projecting portions formed by the depressed portions 41. When the shield and band are expanded by the member 32 or 36 the inner shoulder prevents the band from being forced longitudinally inwardly 115 along the shield as the intermediate shoulder is bent by the action of the expanding member. 120

In Figs. 15 and 16 the shield sections 20 and 21 are depressed throughout the major 130

portion of the length and the metal at the edges of the sections at the depressed portions thereof is folded back on the outer surface of the shield as shown at 43. Each section adjacent the outer end thereof is provided with a depression 44 and a tab 45, the tab of one section seating in the depression of the other section.

In Figs. 17 and 18 the shield is provided with longitudinal corrugations 46 and intermediate depressions 47 and the sections are secured together by tabs 48, each seating in depressions 49 as in the preceding forms of the invention.

The shield above described was particularly designed for use in securing a bridle ring and cable clamp to a wall. In Fig. 19, a cable clamp 50 is illustrated, this clamp having a flange 51 provided with an opening 52 for receiving the shield. The bridle ring 53 has formed thereon an offset flange 54 and this flange has an opening 55 for receiving the shank of the securing and expanding element 32. When the parts are assembled as shown in Fig. 19, the shield is first passed through the opening in the cable clamp flange 51 and the bridle ring is then positioned with its flange 54 abutting the flange 22 of the shield. The expanding and securing element 32 is then inserted through the opening 55 and the flange 54 of the bridle ring and into the shield. This element will then expand the shield into a firm and gripping engagement with the wall opening. In Fig. 20 a bridle ring 56 is illustrated, this ring having a flange 57 and a shank 58. This form of bridle ring may be used without any other expanding or securing element.

In Fig. 21 the bridle ring 59 has formed thereon an annular flange 60 and an integral shank 61.

From the foregoing specification, it will be seen that a very simple and practical expansion shield construction has been designed and that the shield is well adapted to perform the desired functions and accomplish the objects set forth. It will also be noted that this shield is especially adapted for use with cable clamps and bridle rings.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. In combination, an expansion shield comprising a pair of sheet metal sections, each section having tabs thereon overlapping and engaging the other section and having inwardly extending embossments on the inner surface thereof formed by depressions

in the shield, said depressions receiving said tabs, and an expanding element adapted to be driven into the shield from the outer end thereof and having a diameter as great as the maximum inner diameter of the shield, said expanding element being adapted to engage the embossments and force outwardly the embossments and tabs.

2. In combination, an expansion shield comprising a pair of sheet metal sections, each section having tabs thereon overlapping and engaging the other section and having oppositely disposed depressions forming inwardly extending embossments on the inner surface thereof, the tabs being seated in the depressions, and an expanding element adapted to be driven into the shield from the outer end thereof and having a diameter substantially as great as the maximum inner diameter of the shield, said expanding element being adapted to engage the embossments and force outwardly the embossments and tabs.

3. In combination, an expansion shield comprising a pair of sections formed of sheet metal, each section having a plurality of tabs and a plurality of depressions extending into the bore of the shield, said tabs and depressions being so relatively arranged that the tabs of each section engage the depressions in the other section, and an expanding element adapted to be driven into the shield from the outer end thereof and to engage the inwardly extending depressions and force said depressions and tabs outwardly.

4. In combination, a substantially cylindrical expansion shield comprising a pair of sections, each section having tabs thereon overlapping and engaging the other section and having portions thereof depressed forming inwardly extending embossments on the inner surface thereof, said depressions receiving said tabs, and an expanding element adapted to be driven into the shield from the outer end thereof and to engage said embossments and force the embossments and tabs outwardly.

5. A substantially cylindrical expansion shield comprising a pair of sections, means for securing the sections together, said means including depressions forming inwardly extending embossments, decreasing the internal diameter of the shield and excess metal disposed in said depressions, and a driven expanding member adapted to engage the embossments and force the embossments and excess metal outwardly.

6. In combination, a substantially cylindrical expansion shield comprising a pair of sections, said sections being depressed to form a plurality of pairs of inwardly extending oppositely disposed embossments on the inner surface thereof, excess metal on the outer surface of the shield disposed in the depressions and holding said sections together, and an expanding member adapted

to be driven into the shield from the outer end thereof and to engage the embossments and force the shield sections outwardly.

7. In combination, an expansion shield of
5 hard metal having its bore constricted at an intermediate portion of its length and a thin divided flange of non-expansible metal integral with the shield about one end thereof and substantially at right angles to the
10 shield axis, and an expanding element adapted to engage and expand the constricted portion and having a head adapted to overlap and reinforce said flange.

8. In combination, an expansion shield
15 having depressed portions constricting the bore and having a flange at one end thereof, excess metal on the outer surface of the shield disposed in the depressed portions and an expanding element having a head adapted to
20 coact with the flange to reinforce said flange.

9. In combination, an open ended expansion shield having a depressed portion constricting the bore and having a flange at one end thereof, metal disposed on the outer surface of the shield and disposed in the depressed portion and an expanding element having a head adapted to coact with the flange to reinforce said flange.

10. An expansion shield comprising a
30 sheet metal, substantially cylindrical open ended tubular member having a flange at one end extending laterally beyond the outer cylindrical surface of the shield and having depressions formed in and extending into the bore of the member thereby decreasing the internal diameter thereof and metal on the outer surface of the shield disposed in said depressions.

11. An expansion shield comprising a
40 sheet metal tubular member having a flange at the outer end thereof extending laterally beyond the outer cylindrical surface of the shield, said shield having a longitudinal parting therein, said member being depressed at
45 one side of the parting and having a tab bridging the parting and disposed in the depression, the depression constricting the bore of the shield.

12. In combination, an expansion shield
50 formed of sheet metal and having a flange at the outer end thereof and having a depression therein constricting the bore of the shield and forming shoulders at the ends of the depression and metal on the outer surface of the
55 shield and disposed between said shoulders and in the depression, and an expanding element adapted to be driven into the shield from the outer end thereof and having a diameter substantially as great as the maximum inner diameter of the shield.

In witness whereof, I have hereunto set
my hand this 1st day of May, 1923.

RALPH E. OGDEN.
